UNITED STATES PATENT OFFICE.

JOSEPH W. BECK, OF CINCINNATI, OHIO.

WATER-LIFTING DEVICE.

SPECIFICATION forming part of Letters Patent No. 718,414, dated January 13, 1903.

Application filed June 23, 1902. Serial No. 112,778. (No model.)

To all whom it may concern:

Be it known that I, JOSEPH W. BECK, a citizen of the United States, residing at Cincinnati, in the county of Hamilton and State of Ohio, have invented new and useful Improvements in Water-Lifting Devices, of which the following is a specification.

My invention relates to the class of pumping devices commonly known as "air-lifts," devices used in raising water from wells where a current of air under pressure is delivered into the body of water at or near the bottom of the well as a means of lifting a column of water to the surface by a continuous flow.

The object of the invention is to simplify the means employed for this purpose and provide also a means of adjusting the discharge-opening to the depth of submergence and quantity of water to be lifted in order to economize the pressure and quantity of air required to lift a given quantity of water to given heights.

To this end my invention consists in the device herein shown and described embodying a discharge-tube perforated at the bottom, an air-pipe extended from the surface or upper end of the said tube into the body of the water at the bottom of the well, carrying a bell-shaped receiver provided with means for engaging frictionally against the sides of the discharge-tube, the air-pipe engaging the bell-shaped receiver by a threaded connection and carrying a valve which by rotation of the air-pipe in said threaded connection regulates the annular orifice through which the air is discharged into the body of the water.

My invention is illustrated in the accompanying drawings, in which—

Figure 1 is a vertical axial section of the well and of the discharge-tube, showing my device applied thereto. Fig. 2 is an axial section of the bell-shaped receiver, showing details of construction; and Fig. 3, a plan view of the bell-shaped receiver sectioned at $\alpha\alpha$ of Fig. 1.

Referring now to the drawings, A designates a well or cistern, shown here as a well-tube sunk in the ground into the water-bearing stratum indicated. Within the tube or casing A is placed a smaller tube B for lifting

of water, perforated at the bottom for screening purposes and extending outward beyond the casing A through a suitable cover a. If desired, the tube B may be provided with a discharge-valve b. Within the tube B and extending through a water-tight cover b' is an air-pipe C, carried downward to a point beneath the water-level and carrying by a threaded connection, to be more particularly described, a bell-shaped receiver D. The pipe C may also be provided with a regulating-cock c', and its lower end may be contracted, as shown at c, and provided with contracted orifices for discharge of air into the body of the bell-shaped receiver D. The bell-shaped receiver is open above by a cone-shaped orifice somewhat contracted and entirely open below. It is provided at its lower margin with a plurality of elastic curved fingers d' to engage frictionally the side of the tube B to prevent rotation of the bell. Within and at the upper part of the conical throat is cast or secured a "spider," carrying a central perforated boss d, provided with threads to engage corresponding threads of the pipe C, whereby the bell-shaped receiver D is suspended on said pipe. The pipe C carries above its threaded connection a conical valve c', rigidly secured, which stands in a concentric relation to an outward-flaring throat d² of the bell-shaped receiver D, leaving an annular space having a like upward flare between the valve c' and the wall of the flaring throat d². This annular space is narrowed or widened by elevating or depressing the valve c', and this is done by revolving the pipe C in its threaded seat in the boss d, the bell D being held from rotation by the fingers d', in frictional contact with the pipe B. The fingers d' also retain the mouth of the bell in concentric relation with the pipe B, leaving an enlarged annular space by which water passes upward around the bell.

The mode of operation is as follows: The discharge-pipe B, perforated at the bottom, is dropped down within the well-tube A to the bottom, and within the pipe B the bell D, suspended by the air-pipe C, is dropped down into the body of water to a submergence of eighteen inches, more or less, below the water-level. Air is then forced downward into the bell D from an air pump or

- compressor (not shown) as regulated by the cock c^2 and by displacement of water as held in compression therein and issues upward in an annular sheet through the orifice around the valve C' and by impact as well as by lifting force of the air-bubbles lifts the column of water in the discharge-pipe B and discharges the same in a continuous flow at the cock b .
- 10 The action is regulated by the adjustment of the valve C' , and this is accomplished by rotating the pipe C in its threaded boss d , so as to reduce the air flow to that required, thus preventing all unnecessary waste of air in raising the desired amount of water.
- I claim as my invention and desire to secure by Letters Patent of the United States—
1. In a water-lifting device the combination of a discharge-tube open or perforated at the bottom, an air-tube carried downward within the same, and an air-receiver connected therewith, said receiver entirely open below and provided with an annular contracted throat opening upward for discharge of air, substantially as set forth.
2. In a water-lifting device, the combination of a discharge-tube open or perforated at the bottom, an air-tube carried downward within the same, and an enlarged open-bottomed air-receiver connected therewith

provided with an annular opening provided with an adjustable conical plug or valve for regulating the discharge upward of an annular current of air, substantially as set forth.

3. In a device of the character indicated 35 the combination of an air-pipe, an air-receiver suspended thereon by a threaded connection, elastic fingers carried by the lower end of the receiver, and a conical plug or valve carried on said pipe and adjusted in the relation to 40 the receiver-orifice by rotation of the air-pipe in its threaded connection with the air-chamber, substantially as and for the purpose set forth.

4. The combination in a device of the character indicated, of the discharge-tube, the air-tube, the air-chamber, suspended upon the same by the threaded connection and having the elastic fingers attached to contact with the walls of the discharge-tube, and the 45 conical valve or plug upon the in pipe, substantially as and for the purpose set forth.

In testimony whereof I have hereunto set my hand in presence of two subscribing witnesses.

JOSEPH W. BECK.
